UNITED STATES PATENT OFFICE

RUDOLF KIRSCH, OF FRANKFORT-ON-THE-MAIN, GERMANY, ASSIGNOR TO KARL MAX-
ANER, OF CELLE-KL. HEHLEN, GERMANY

CALENDAR

Application filed July 31, 1930, Serial No. 472,035, and in Germany August 2, 1929.

The present invention relates to calendars, and more particularly to calendars of that type which are in block form and are suitable either for hanging on a wall or for use 5 on writing tables, desks, etc.

It is the object of the invention to generally improve on calendars of the kind referred to, and this is accomplished in the manner hereinafter described. Other objects and advantages obtained will become apparent as 10 the description proceeds.

The desire to make calendars lucid, tasteful and at the same time economical, for example by utilizing the free spaces on the 15 single leaves for advertising purposes, saving of paper, etc., has led to various forms of embodiment.

In employing these calendars, for example in card form, the containers for the cards are 20 apt to be of complicated construction.

An entirely different method of obtaining the same advantages is adopted by the subject matter of invention, which consists of a calendar of the block type suitable either for 25 adorning a wall or for use on writing tables, desks, etc. and at the same time suitable for the display of advertising matter. The invention resides in the fact that the single leaves of the calendar are composed of a 30 transparent material on which there are provided opaque sections bearing the date and the day, the name of the month being furnished on a separate opaque sheet arranged at the back of the transparent day 35 sheet, so that the name of the month is visible through all transparent sheets arranged in front thereof.

A particularly advantageous form of embodiment is obtained by utilizing the remaining portions of the opaque sheet bearing 40 the name of the month for the display of advertising matter, announcements, etc., which thus remain visible through the transparent day sheets throughout the whole month.

The transparent day sheets are preferably 45 furnished with an opaque portion for making notes, reminders, etc.

The invention is illustrated by way of 50 example in the accompanying drawing, in which

Fig. 1 is a front view of the calendar,
Fig. 2 an elevation,
Fig. 3 a single transparent day sheet, and
Fig. 4 an opaque sheet bearing the name of 55 the month.

In accordance with the particular day of the month the transparent sheets 1 furnished with the day of the week 2 and the date 3 are united in block formation with an opaque sheet 4, bearing the name of the 60 month 5, advertising matter 6 or any other desired inscription. On the transparent sheets 1 there may also be provided an opaque portion 7, which permits of notations or any other form of record being made. 65 The surfaces, on which the names of the week days and the dates are printed, are made dark, as compared with the free parts of the sheets in question, or may be so constructed that they are opaque. The rendering opaque 70 or covering may, for example, be effected by printing with a suitable white or light colored ink, preferably by means of a body paint, which can be written upon with ink or pencil for the note space 7.

The use of transparent sheets for the purpose in question offers quite important advantages and also a very considerable amount of saving. In the first place considerable saving is effected as regards printing, as the 80 majority of inscriptions such as the day of the month, name of the month, number of days in the month, etc., which have hitherto been printed on each single sheet, require to be printed only once for each month. It has 85 hitherto been necessary to print these inscriptions roughly thirty times for each month. By using the transparent sheet according to the invention in place of the usual paper each month necessitates merely one 90 print, and the arrangement is preferably such that a dark blue printed sheet of the size of the calendar sheet is inserted after each calendar month. This sheet is furnished with the inscriptions referred to above, which 95 recur each day throughout the month. Printing is preferably performed with a bright, high grade ink, for example chrome yellow in color. Suitable phosphorescent colors luminous at night may also be em- 100

ployed. For obtaining a novel and very effective form of advertisement suitable announcements, for example advertising the products of the firm issuing the calendar, may also be included on the printed sheet, these being in the same bright color as the remaining matter. By reason of the transparency of the sheets employed in place of the usual opaque paper sheets both the actual calendar inscriptions as well as the advertising matter are brought daily to notice, which considerably increases the effect of the advertisement. The printed sheet may vary from month to month, for example the advertising matter on the one sheet differing to that on the sheet for the preceding month, and as before the matter in question will be brought daily to notice each day throughout the month. There is no doubt that this entirely novel method of advertising offers considerable advantages, as during the course of one complete year a large number of products may be brought daily to notice without any considerable expense incurred by printing. The effect of the advertisement or announcement is moreover in so far novel as by the use of the brightly colored ink on the dark blue paper a transparent "window" advertisement is obtained having an interior lighting effect. This lighting effect is amplified each day as the month proceeds. The effect in question is obtained chiefly by the use of the transparent sheets and is amplified by the employment of suitable and striking colors. By the fact that printing is required only once for each month there is a considerable saving as regards printing costs. Whereas in the case of a normal year it has been necessary with calendars of the usual type having ordinary paper leaves to print both the actual calendar inscriptions as well as the particular advertising matter 365 times, it is merely necessary according to the invention to print the majority of the inscriptions, including the whole of the advertising matter, twelve times, whereby the effect of the advertisement thus obtained is distinctly novel as compared with heretofore. The opaque surfaces of the sheets may consist of body white, whereas for the printing of the dates and week days, a black or dark green may, for example, be employed. It will be understood that no restriction is made to the specific form of embodiment shown in the drawing, and that various modifications are quite possible within the meaning of the above and the annexed claims without departing from the spirit of the invention.

60. What I claim as new and desire to secure by Letters Patent is:

1. In a calendar of the block type, transparent sheets for the dates and the days of the week, opaque portions on the said transparent sheets bearing the said dates and days,

and opaque sheets each bearing the particular month and adapted to be situated behind the said transparent sheets and be visible through the same.

2. In a calendar of the block type, transparent sheets for the dates and the days of the week, opaque portions on the said transparent sheets bearing the said dates and days, and opaque sheets each bearing the particular month and also advertising matter, announcements, etc., and adapted to be situated behind the said transparent sheets and be visible through the same. 70

3. In a calendar of the block type, transparent sheets for the dates and the days of the week, opaque portions on the said transparent sheets bearing the said dates and days, additional opaque portions on the said transparent sheets for the purpose of making notes, and opaque sheets each bearing the particular month and any other desired matter and adapted to be situated behind the said transparent sheets and be visible through the same. 80

4. In a calendar of the block type, transparent sheets for the dates and the days of the week, opaque portions on the said transparent sheets bearing the said dates and days and any other desired matter, and opaque sheets each bearing the particular month and any other desired matter in bright coloration on a dark background, and adapted to be situated behind the said transparent sheets and be visible through the same. 90

5. In a calendar of the block type, transparent sheets for the dates and the days of the week, opaque portions on the said transparent sheets bearing the said dates and days and any other desired matter, and opaque sheets each bearing the particular month and any other desired matter in phosphorescent coloration on a dark background, and adapted to be situated behind the said transparent sheets and be visible through the same. 100

6. In a calendar of the block type, transparent sheets for the dates and the days of the week, opaque portions on the said transparent sheets bearing the said dates and days and any other desired matter, and opaque sheets each bearing the particular month and any other desired matter in fluorescent coloration on a dark background, and adapted to be situated behind the said transparent sheets and be visible through the same. 110

7. In a calendar of the block type, transparent sheets for the dates and the days of the week, opaque portions on the said transparent sheets bearing the said dates and days, and opaque sheets each bearing the particular month and any other desired information such as year, holidays, number of days in the month, etc., and adapted to be situated behind the said transparent sheets and be visible through the same. 120

8. In a calendar of the block type, trans- 130

- parent sheets for the dates and the days of the week consisting of transparent foil having a transparency equivalent to that of glass, opaque portions on the said transparent sheets bearing the said dates and days, and opaque sheets each bearing the particular month and any other desired matter and adapted to be situated behind the said transparent sheets and be visible through the same.
- 10 9. In a form of embodiment of a calendar of the block type, transparent sheets for the dates and the days of the week, opaque portions on the said transparent sheets bearing the said dates and days, additional opaque portions on the said transparent sheets for the purpose of making notes, and opaque sheets each bearing the particular month and any other desired information, advertising matter, announcements, etc., in bright coloration
- 15 20 on a dark background, and adapted to be situated behind the said transparent sheets and be visible through the same.
- 25 10. In a form of embodiment of a calendar of the block type, transparent sheets for the dates and the days of the week, opaque portions on the said transparent sheets bearing the said dates and days, additional opaque portions on the said transparent sheets for the purpose of making notes, and opaque
- 30 sheets each bearing the particular month and any other desired information, advertising matter, announcements, etc., in luminous colors on a dark background, and adapted to be situated behind the said transparent sheets
- 35 and be visible through the same.

In testimony whereof I have affixed my signature.

RUDOLF KIRSCH.
